UNITED STATES PATENT OFFICE

2,656,831

VARIABLE THROWING ANGLE TARGET PROJECTOR

George J. Puth, Appleton, Wis.

Application March 24, 1952, Serial No. 278,159

6 Claims. (Cl. 124—9)

1

This invention relates to new and useful improvements in target traps and the primary object of the present invention is to provide a target projector including a cocking lever attached to a spring actuated throwing arm and so constructed as to obviate tension on the spring or arm unless the operator pulls the cocking lever rearwardly.

Another important object of the present invention is to provide a target projector including a vertically swingable throwing mechanism and novel and improved means for adjusting the mechanism about the pivot to vary the trajectory of a target projected by the mechanism.

A further object of the present invention is to provide a target projector of the aforementioned character including a single lever for cocking the throwing mechanism, releasing the holding means for the throwing arm of the mechanism, and actuating the adjusting means.

A still further aim of the present invention is to provide a target trap that is simple and practical in construction, strong and reliable in use, efficient and durable in operation, small and compact in structure, inexpensive to manufacture, and otherwise well adapted for the purpose for which the same is intended.

Other objects and advantages reside in the details of construction and operations as more fully hereinafter described and claimed, reference being had to the accompanying drawings forming part thereof, wherein like numerals refer to like parts throughout, and in which:

Figure 1 is a side elevational view of the present invention;

Figure 2 is a plan view of Figure 1;

Figure 3 is an enlarged fragmentary view of Figure 1 and showing the lever pulled rearwardly and about to release the holder for the target throwing arm;

Figure 4 is a view similar to Figure 3 but showing the throwing arm in its forward position after projecting a target;

Figure 5 is a fragmentary plan view of Figure 4;

Figure 6 is a fragmentary view of Figure 3 showing the manner in which the throwing mechanism is adjustable about its pivot;

Figure 7 is an enlarged detail sectional view taken substantially on the plane of section line 7—7 of Figure 1; and,

Figure 8 is an enlarged detail sectional view taken substantially on the plane of section line 8—8 of Figure 1.

Referring now to the drawings in detail, wherein for the purpose of illustration, there is disclosed a preferred embodiment of the present in-

2

vention, the numeral 10 represents a base preferably in the form of a tripod having a supporting hollow post 12 and legs 14 fixed to the post.

A frame 16 is rotatably supported on the base 10 and includes an elongated member 18 one end of which supports a seat 20 and the other end of which fixedly supports a depending vertical arm 22. Arm 22 extends downwardly into the post 12 and through bearing races 24 and 26 held in the post 12 by suitable means.

A flange 28 is rigidly secured to the post 12 and removably supports a pair of diametrically opposed vertical stop pins 30 which will engage the member 18 to limit horizontal swinging movement of the frame 16 to approximately 120 degrees. Pins 30 may be removed in order to permit complete 360 degrees rotation of the frame 16 on the base 10.

The end of the member 18 disposed above the base 10 supports a plate member 32 to which a target throwing mechanism 34 is pivotally secured. The mechanism 34 includes a pair of clamping plates 36 that straddle the plate member 32. A horizontal pivot 38 secures the plate member 32 and the plates 36 together.

The periphery of a sleeve 40 is fixed to at least one of the plates 36 by welding or the like. The sleeve 40 is also fixed to a U-shaped support member 42 whose forward end is attached to a bearing sleeve 44.

A target throwing arm 46 is fixed at one end to a pivot 48 that extends downwardly through the bearing sleeve 44. A rigid link 50 is removably secured to the lower end of the pivot 48 and parallels the arm 46. The outer end of link 50 is attached to the forward end of a tightly coiled spring 52 whose rear end fixedly supports a short bar 54.

The lower end of a lever 56 is pivoted, as at 58a, to the plates 36 and an intermediate portion of the lever 56 is pivoted to the bar 54, whereby the spring 52 may be extended. The lever 56 may also be employed for cocking arm 46 in a manner presently to be more fully described. A hand grip 57 is secured over the upper end of the lever 56.

A rigid bar element 58 is secured to the upper face of arm 46 by spacers 60. One edge of the bar element 58 supports a resilient strip 62 against which a target will rest that is supported on the arm 46.

A holder 64 is pivoted on the forward end of member 42 behind the pivot 48 and includes a pair of upstanding laterally spaced lugs 66 for engaging a lug 68 on the undersurface of the arm 46 when the arm 46 is pulled rearwardly, in order to retain the arm 46 retracted.

Means is provided for releasing the arm holding means 64, 66. The releasing means comprises a rod 70 having a forward end pivoted to the holder 64 and a rear end that extends through an eye 72 fixed to an L-shaped releaser 74 pivoted to the rear end of member 42. Nuts 76 are threaded on the rear end of rod 70 and a coil spring 78 embraces the rear end of the rod 70 and is biased between the nuts 76 and the eye 72 to yieldingly urge the rod 70 rearwardly and the lugs 66 into engagement with lug 68. The shorter leg of releaser 74 extends across the member 42 behind the lever 56.

Means is provided for adjusting the mechanism 34 about its pivot 38. This means comprises a ratchet 80 that is eccentrically pivoted to a U-shaped bracket 82 fixed to the mechanism 34 by a pair of spaced parallel arms 83. A pawl 84 is secured to the bar 54 for engaging the ratchet to actuate rotation of the ratchet. A seat 86 is fixed to the member 18 under the ratchet for selectively engaging the teeth of the ratchet.

Spring 52 extends through the sleeve 40 and is retained against lateral movement in the sleeve 40 by a spacer lug 88. Sleeve 40 supports a spring 90 that is attached to the link 50 to limit and cushion forward movement of the arm 46 relative to the frame.

A coil spring 92 is terminally secured to the member 42 and the member 18 to urge the forward end of the member 42 upwardly as shown best in Figure 3.

A retainer arm 94 is fixed to the member 42 and includes a laterally projecting flange 96 that will pass over arm 46 as the arm 46 is pulled rearwardly, to form a supporting ledge for a target resting on arm 46.

In practical use of the present invention, the lever 56 may be rocked back and forth so that pawl 84 will engage and rotate ratchet 80 until the mechanism 34 is adjusted about the pivot 38 to a desired position.

Then the lever 56 is forced forwardly by hand grip 57 so that spring 52 will be moved forwardly to rotate pivot 48 and swing arm 46 rearwardly where lug 68 engages lugs 66 to retain the arm 46 retracted. A target is next placed on the arm 46 and rests against flange 96 and strip 62.

Lever 56 is pulled rearwardly by hand grip 57 and since the rear end of spring 52 is attached to the lever 56, the spring 52 will be expanded. Continued rearward pull on lever 56 by an operator seated on the seat 20 and grasping hand grip 57 will cause the lever to engage releaser 74 pulling rod 70 rearwardly until holder 64 releases lug 68. The spring 52 then causes the arm 46 to swing forwardly to project the target into the air.

Having described the invention, what is claimed as new is:

1. A target projector comprising a base, a frame rotatably supported on the base, a target throwing mechanism vertically pivotally mounted on the frame and including a swingable throwing arm, a spring member attached to said arm for imparting swinging movement to the arm, a cocking lever pivotally mounted on the mechanism and engaging the spring member to extend the latter as the lever is pulled rearwardly, a holder forming part of the mechanism for engaging and holding the arm retracted, said arm being engaged with said holder during forward movement of the lever, releasing means for the holder actuated by said lever during rearward movement of the lever, and means carried by the mecha-

nism engaging said frame and actuated by said lever for adjusting the mechanism about its pivot.

2. The combination of claim 1, wherein said adjusting means comprises a ratchet eccentrically pivotally attached to the mechanism, a seat on the frame selectively engaging the teeth of the ratchet, and a pawl attached to the spring member and engaging the ratchet.

3. A target projector comprising a base, a frame rotatably supported on the base, a vertically swingable target throwing mechanism pivoted to the frame and including a swingable throwing arm, a spring attached to the arm for swinging the arm forwardly, means engageable with the arm for retaining the arm in a rearward position, a combined cocking and actuating lever pivotally attached to the mechanism for rearward and forward pivotal movement, said lever being attached to the spring to extend the spring as the lever is pulled rearwardly for moving the arm into engagement with said retaining means as the lever is moved forwardly, a releasing means for the retaining means including a part disposed behind and in the path of the lever to release the retaining means as the lever is pulled rearwardly, and means actuated by the lever for adjusting the mechanism about the pivot thereof to vary the trajectory of a target projected by the arm.

4. A target projector comprising a base, a frame rotatably supported on the base, a vertically swingable target throwing mechanism pivoted to the frame and including a swingable throwing arm, a spring attached to the arm for swinging the arm forwardly, means engageable with the arm for retaining the arm in a rearward position, a combined cocking and actuating lever pivotally attached to the mechanism for rearward and forward pivotal movement, said lever being attached to the spring to extend the spring as the lever is pulled rearwardly and for moving the arm into engagement with said retaining means as the lever is moved forwardly, a releasing means for the retaining means including a part disposed behind and in the path of the lever to release the retaining means as the lever is pulled rearwardly, a ratchet eccentrically rotatably secured to the mechanism, said frame having a seat selectively engaging the teeth of the ratchet to adjust the mechanism about its pivot to vary the trajectory of a target projected by the arm, and a pawl attached to the spring and engaging the ratchet to permit step by step rotation of the ratchet as the lever is actuated.

5. A target trap comprising a base, a horizontally swingable frame rotatably supported on the base, a target throwing mechanism, a pivot securing the mechanism to the frame and permitting vertical swinging movement of the mechanism relative to the frame, said mechanism including a forwardly and rearwardly swingable throwing arm pivotally mounted on the mechanism, a holder on the mechanism engageable with the arm during rearward movement of the arm to hold the arm in a rearward position, a spring attached to the arm for urging the arm forwardly, tilt means carried by the mechanism engaging the frame for adjusting the mechanism about said pivot, and a single forwardly and rearwardly swingable lever pivoted to the mechanism and attached to the spring, and means carried by the lever engageable with the tilt means for adjusting the tilt means, said lever having the three fold function of cocking the arm, releasing the holder and actuating the adjusting means.

6. A target trap comprising a base, a horizontally swingable frame rotatably supported on the base, a target throwing mechanism, a pivot securing the mechanism to the frame and permitting vertical swinging movement of the mechanism relative to the frame said mechanism including a forwardly and rearwardly swingable throwing arm pivotally mounted on the mechanism, a holder on the mechanism engageable with the arm during rearward movement of the arm to hold the arm in a rearward position, a spring attached to the arm for urging the arm forwardly, means carried by the mechanism engaging the frame for adjusting the mechanism about said pivot, a forwardly and rearwardly swingable lever pivoted to the mechanism and attached to the spring for extending the spring as the lever is pulled rearwardly and for swinging the arm rear-

wardly into engagement with the holder as the lever is moved forwardly, means disposed in the path of the lever and engaged with the holder for releasing the holder as the lever is pulled rearwardly, and means carried by the lever engaging and actuating said adjusting means.
